TRAFFIC RATE FINDING MACHINE

Joseph M. Johnson, Birmingham, Ala.

Application September 29, 1941, Serial No. 412,821

3 Claims. (Cl. 129—16.1)

This invention relates to traffic rates and has for its main object to provide a machine that will make it easy to find the desired rate. At present it requires a lot of time and trouble as it is necessary to consult one or more rate books or schedules in order to arrive at the proper rate covering the distance and commodity. The present invention as a rate finding machine overcomes the antiquated method.

By referring to the drawings, part of this application, it will be observed that Fig. 1 is a plan view of the machine; Fig. 2 is a front elevation view; Fig. 3 is an end elevation in section on line 3—3 of Fig. 1; Fig. 4 is a part side view of the machine on line 4—4 of Fig. 3; Fig. 5 is a detail view of a rate card used in the machine; Fig. 6 is a detail view of a card carrying frame or holder; Fig. 7 is a side view of a card carrying frame or holder; Fig. 8 is a detail view showing mechanism for putting a card and holder back in the machine cylinder; Fig. 9 is a detail view showing mechanism for placing a card and holder in sight to read; and Fig. 10 is a diagram showing the movement of cross arm 20 and vertical bars or connections 16 and 17.

Similar reference numerals refer to similar parts throughout the drawings.

Again referring to the drawings it will be seen that the machine comprises a case or frame having sides 1, top 2, base 3, and front 42. Supported in the frame on a shaft 9 in bearing 36 at each end is a main cylinder 30 having divisions for rate cards, the first division 10 having rate cards ranging from 0 to 99 cents; the second division 11 having rate cards ranging from 100 to 199 cents; the third division 12 having rate cards ranging from 200 to 299 cents; the fourth division 13 having rate cards ranging from 300 to 399 cents; the fifth division 14 having rate cards ranging from 400 to 499 cents. These cards 31 have the rate figures on them as shown in Fig. 5. Each card is supported in a frame or holder 29 that is carried on a pivot bearing 34 in the form of a circular ring-shaped shaft. The card frame has a short arm or dog 33 that is set in a forked trigger 32 mounted on a bearing 35 fixed on a shaft 15.

The front of the machine has a dial 4 with holes indicated by 39 that are uniformly spaced around the edge of its face into which holes a pin 44 is carried in a pointer arm 5 like a clock hand which is mounted on dial 4. This dial is also provided with numerals spaced around its face inside the circumference indicated by the holes 39 at the position shown by 43. Each hole

registers with a numeral. This front dial is fixed but the pointer arm 5 on it is attached to a shaft 6 that is carried in a bearing 37 that is supported on the frame front 42. This shaft 6 has a bevel gear 7 that coacts with a companion bevel gear 8 that is mounted on the cylinder carrying shaft 9. The cards are exposed through an opening 40 along the cylinder.

The operating keys are indicated by 23, 24, 25, 10 26 and 27 for the exposing or ejecting the cards for reading, and key indicated by 28 is for the return of the exposed card after reading. When any rate up to 99 cents is wanted the dial indicator arm 5 is set thus causing rotation of the cylinder 30 to place the particular card 31 beneath the opening 40, and to place the arm 33 of the corresponding card holder 29 into engagement with its respective forked trigger 32. After that the key 23 is pushed which acts through its connections 16 and 21 that act on cross arm 20 that is connected to the shaft to rotate the shaft 15 and thus operate the trigger. When return key 28 is pushed it returns the card to rest position by acting on the rocker arm 20 at its 20 other end 18. The key operation is shown in 15 Fig. 10. One position being indicated by 16, 17, 20, 22 and 23; the opposite position being indicated by 16a, 17a, 20a, 22a, and 23a. In Fig. 8 the card frame is shown at rest position indicated by 29, and by out position for reading indicated by 29a. The return key operates in one of the 25 guide slots 41 and is supported in its proper place on two coil springs 38.

The front dial and arm indicator are synchronized with reference to dial numbers and card frames so that the desired rate card will be placed in exposed position on pushing the key for the rate structure wanted. For instance a rate ranging from 1 to 99 cents would be covered by key 23 and so on. The card frames are carried in each section of the main cylinder in the same manner as letter arms on a typewriter and are picked out by the trigger mechanism that is synchronized with the number and hole 30 on the dial.

While I have shown the preferred embodiment of my invention I do not wish to limit myself to the precise and exact details of structure but reserve the right to make any and all modifications 35 and changes so long as I remain within the spirit and scope of the following claims.

Having described my invention I claim:

1. A traffic rate finding machine comprising; 40 a main cylinder divided into a plurality of compartments, a circular shaft at one side of each

of the compartments, said cylinder mounted on a shaft supported in a bearing at each end, said bearings supported in a main case of the machine, a plurality of card frames and cards therein supported on each circular shaft, each of said cards having marked thereon a traffic rate structure; a dial and indicating pointer mounted on the front of the machine frame, said dial having uniformly spaced around its face edge a plurality of holes and numerals, a pin in the pointer on the dial disposed to be set in any one of said holes, a plurality of operating keys mounted on the front of said machine disposed to operate lever and trigger means in the machine to expose any selected one of said rate cards to view depending upon the particular position of said pointer, a returning key mounted on the front of the machine disposed to operate lever and trigger means to return any exposed card to rest position; said dial indicator attached to a shaft having a bevel gear on its opposite end, said bevel gear coacting with a similar gear mounted on the main shaft of the cylinder; said dial, dial indicator, keys, and card frames all synchronized and disposed to work in unison.

2. A traffic rate finding machine comprising in combination; a main cylinder divided into a plurality of compartments, each of said compartments containing a plurality of V shaped frames pivotally mounted at one corner on a shaft, each of said frames having an extending arm that fits trigger means, said trigger means having connecting rods leading to a key mounted on the front of the machine; each of said frames containing a card having traffic rate structure marked thereon, one compartment of said cylinder containing rate cards ranging from one cent to 99 cents, another of said compartments containing rate cards ranging from 100 to 199 cents, another of said compartments containing rate cards ranging from 200 to 299 cents, another of said compartments containing rate cards ranging from 300 to 399 cents, another of said compartments containing rate cards ranging from 400 to 499 cents; said cylinder mounted on a shaft supported in a bearing at each end, said bearings supported in a main frame of the machine; a dial and indicating pointer mounted on the front of the machine frame, said dial having uniformly spaced around its face edge a plurality of holes and numerals, a movable pin in the pointer on the dial disposed to be set in any one of said holes, a plurality of operating keys mount-

ed on the front of the machine and disposed to operate lever and said connecting rods and trigger means in the machine to expose any selected one of said rate cards to view depending upon the particular position of said pointer, a returning key mounted on the front of the machine disposed to operate said lever, rod and trigger means to return any exposed card to rest position; said cylinder case having a slot along its top to permit the exposing and returning of said card frames; said dial and indicating pointer synchronized with said plurality of card frames through a shaft on which said pointer is attached, said shaft having a bevel gear on its opposite end, said bevel gear coacting with a similar gear mounted on the main cylinder shaft, substantially as described.

3. A traffic rate finding machine comprising a main case, a cylinder supported on a shaft in bearings in said case, said cylinder divided into a plurality of compartments, in each compartment a plurality of card holding V shaped frames mounted pivotally, a card in each of said frames, inscribed on each card a traffic rate combination, each of said frames disposed to be selected at will; a dial mounted on the front of the machine case, a pointer clock-like hand on said dial, said dial having a plurality of holes and numerals uniformly placed and spaced around its outer face edge, said dial indicator disposed to be set to select any of said rate card frames, the cards in said frames ranging in rates from 1 to 499 cents; on the front of the machine case a plurality of keys, each of said keys when pushed downward disposed to expose to view the rate card of the corresponding compartment selected on said dial, each of said keys controlling the said card frames in one compartment; a return key mounted on the front of said machine case disposed when pushed downward to return to rest position the card frame and card previously exposed to view by means of either exposing key; all said keys connected by rod and trigger means to said card frames; said cards and frames being designated as to position in the cylinder by said holes and numerals on the said dial; the pointer hand on the dial having a movable pin for setting in any desired hole adjacent the numeral corresponding to the card frame; said pointer hand disposed by shaft and gear means to revolve equally with said cylinder, substantially as described.

JOSEPH M. JOHNSON.
